UNITED STATES PATENT OFFICE.

HENRY PRICE BALL, OF BROOKLYN, NEW YORK, ASSIGNOR TO S. STERNAU & CO., INC.,
OF NEW YORK, N. Y., A CORPORATION OF NEW YORK.

STOVE.

1,411,250.

Specification of Letters Patent. Patented Apr. 4, 1922.

Application filed September 15, 1920. Serial No. 410,442.

To all whom it may concern:

Be it known that I, HENRY PRICE BALL, a citizen of the United States, and a resident of the borough of Brooklyn, county of 5 Kings, city and State of New York, have invented a certain new and useful Stove, of which the following is a specification.

The invention relates to stoves for burning alcohol fuel, and more particularly to 10 such devices in which solidified alcohol is employed as the fuel and, while the invention is of general adaptability, the embodiment of the invention illustrated is particularly designed for use in connection with a 15 grill or grid, such as is illustrated in applicant's Patent No. 1,373,788 of April 5, 1921.

The objects of the invention are to provide 20 a device of the character described wherein fuel may be burned in the container in which it is marketed; in which a plurality of such containers may be employed; in which the positions of the containers may be adjusted to facilitate replacement; in which the intensity of the flame may be 25 regulated; in which the flame may be extinguished; in which air may be properly supplied to the container to support combustion of the fuel therein; which will be cheap to construct, and which will be of 30 rugged construction and not liable to get out of order.

These and further objects will more fully appear in the following specification and accompanying drawings considered together 35 or separately.

One embodiment of the invention is illustrated in the accompanying drawings, in which like parts in all of the several figures are designated by similar characters of 40 reference, and in which

Fig. 1 is a top plan view of a stove embodying the invention showing the same in position of full flame.

Fig. 2 is a fragmentary top plan view of 45 the same showing the position of reduced flame.

Fig. 3 is a section on the line 3—3 of Fig. 1.

Fig. 3^a is a section on the line a—a of 50 Fig. 3.

Fig. 4 is a top plan view of the pedestal or support.

Fig. 5 is a detail sectional view of a portion of the device, the section being taken on the line indicated by 5—5 on Fig. 4. 55

Fig. 6 is a detail elevation, partly in section, showing a modification.

Fig. 7 is a top plan view of the fuel support.

Fig. 8 is a section on the line 8—8 showing the fuel receptacles in position.

Fig. 9 is a side elevation of the device.

Fig. 10 is a partial top plan view, partly in section, of the stove showing the same in position to extinguish the flame. 65

Fig. 11 is a section on the line 11—11 of Fig. 1 showing a fuel receptacle in position, and

Fig. 12 is a plan view of the turntable showing a modification. 70

The invention comprises a base 1 supported on feet 2, which may be positioned in sockets 3 formed in a brick-work or other foundation 4 as shown in Fig. 9, and having a pedestal 5 projecting vertically upward 75 therefrom. The pedestal is provided with a lug 6 projecting radially therefrom, and may have a flat top as shown in Figs. 3 and 5, or it may carry an anti-friction roller 7 as shown in Fig. 6. The base is provided 80 with a plurality of equally spaced, horizontally arranged rollers 8 as shown.

A frame 9 having a central opening 10 is positioned on the pedestal 5 and is rotatable thereon, there being a plurality of 85 slots 10^a grouped around the central opening in the frame whereby the latter may pass the lug 6. The central portion of the frame is provided with a series of grooves 11 equal in number to the rollers 8 on the 90 base whereby when the grooves engage the rollers, as shown in Fig. 9, the frame is locked against accidental rotation on the pedestal, but, by the application of slight force, the grooves may be released from the 95 roller, and the frame rotated.

Radially arranged on the frame 9 is a plurality of rings 12 each having an internal diameter of a size sufficient to receive a cylindrical can 13 of solidified alcohol 100 or other fuel, each of which is preferably provided with a flame opening of a diameter smaller than that of the can. A bar 14 extends across the lower end of each

ring to support the can. The outer edge of each ring is provided with a series of axially projecting lugs 15 whereby a can of greater diameter may be supported upon 5 the top of the ring and be retained in position thereon by the lugs.

Carried upon the pedestal 5 is a top plate or turntable 16 provided with an elongated hub 17 which engages the pedestal. A portion 10 of the turntable projects over the top of the pedestal and the weight of the turntable is supported by the engagement of the portion 18 with the top of the pedestal. A pin 19 projects axially from the pedestal and is adapted to engage any one of three openings 20, 21 or 22 in the portion 15 and lock the turntable in any one of three positions and against rotation.

The hub of the turntable is provided with 20 a groove 23 whereby the hub may be passed over the lug 6, and the upper portion of the groove is widened to permit of rotary movement of the turntable to the limit defined by the openings 20 and 22.

25 A radially extending rod 24 is journaled in bearings on the upper face of the turntable and is provided at its outer end, at some distance from the turntable, with an insulating handle 25. At its inner end, and 30 over the axial center of the pedestal 5 the rod is provided with a cam 26 whereby when the rod is rotated the cam engaging the top of the pedestal, or the roller 7 as the case may be, will elevate the turntable and detach the opening 20, 21 or 22 from the pin 19 whereby the turntable may be rotated to bring another of said openings in alignment with said pin.

The turntable 16 is provided with a series 40 of chimneys 27 corresponding in number and in radial and angular position with the rings 12 and with the cans 13. The chimneys project above the turntable as shown, and in proximity to each chimney the turntable is provided with a crescent shaped opening 28, 45 which opening is preferably wider at the top than at the bottom as shown. The diameter of the chimney opening plus the width of the crescent shaped opening will be approximately equal the diameter of the flame opening in the can.

The operation is as follows:—

The various parts of the device are assembled as described and the stove is placed 55 upon the hearth or other foundation with the rod 25 projecting toward the operator, there being means, such for example as the grid or grill before referred to for supporting food to be cooked, positioned above and 60 independently of the stove.

The operator will rotate the rod 25 and the eccentric cam 26 engaging the top of the pedestal will elevate the turntable 16 to the position shown in dotted lines in Fig. 3.

65 The operator will now place an open can of

fuel in or on the ring 12 nearest him, and light the fuel therein. He will then rotate the frame one notch and bring the next ring to the front and place a can therein and light it. This operation will be continued until 70 each of the rings contains a lighted can of fuel.

The turntable is now rotated by means of the handle until each chimney 27 and its adjacent opening 28 come into axial alignment 75 with each can 13, when the rod 25 is rotated, lowering the turntable into contact with the tops of the cans. The pin 19 will enter the opening 20 and the turntable will be locked against rotation.

80 The top of the chimney being above the level of the turntable a draught will be set up through each chimney and air to support combustion in the cans will be drawn downward into the cans through the opening 28 85 adjacent each chimney. The shape of the opening partially encircling the chimney opening, the area of the opening, and its wedge shape from top to bottom, all serve to direct air downward in quantity to properly support combustion in the can not only when the surface of the fuel is near the top of the can but as such surface recedes, and when the last particle of fuel is in the can, air will be directed to the bottom thereof, 95 and all of the fuel will be consumed.

90 When it is desired to reduce the intensity of the flame the rod 25 is rotated and the turntable is raised as before. The rod is now moved to the left and the turntable rotated until the opening 21 is positioned over the pin 19 when the turntable is lowered and the pin engaging the opening 21 will lock the turntable against further rotary movement. The chimneys and openings 28 are 100 now in position relatively to the flame openings in the cans shown in Fig. 2. This will materially reduce the size and intensity of the flame but sufficient air to support combustion will be admitted.

105 When it is desired to extinguish the flame, the turntable is again raised, and the handle moved to the left until the opening 22 is in alignment with the pin 19. When the turntable is lowered the chimneys and openings 110 will be in the position, relatively to the can flame openings, shown in Fig. 10 and, when the turntable is lowered by the rotation of the handle, it will rest upon the tops of the cans and the flames will be extinguished.

115 The chimneys are so positioned relatively to the center of the turntable that the flames will be so concentrated that a large area of the utensil or other object to be heated will receive the maximum amount of heat, and the source of heat will be sufficiently removed from the operator as to prevent injury or inconvenience to him.

120 The shape of the draught opening 28, and its size and position relatively to the chim-

ney, and the proportion of each relatively to the flame opening in the container are of importance. The crescent shape of the opening permits of the greatest size possible and the maximum amount of air may be drawn into the can to support combustion. By placing the opening to one side of the chimney the cross sectional area of the flame passing through the chimney will not be substantially reduced by a surrounding current of cold air moving in the opposite direction. The location of the draught opening to one side of the chimney is particularly advantageous when the device is used with reduced flames, as practically the entire draught opening may be in use while the flame opening is materially reduced.

The fact that the draught opening is wider at the top than at the bottom will have the effect of an injector, and the column of in-rushing air being reduced in area as it passes through the opening its speed will be accelerated and the speed of the in-rushing air will be directed well into the can and even to the bottom thereof when the surface of the burning fuel is at the lowest level.

It is to be understood that the invention is not limited to use with supports and chimneys for four cans, but any desired number may be employed. When the occasion requires it the flames of as many of the cans as desired may be extinguished by placing an individual cap or cover on such cans, and the frame 9 may be rotated independently of the rest of the apparatus to bring the cans to the accessible position.

In Fig. 12 is shown a modification in which there is an extra chimney 27^a and an extra draught opening 28^a, situated mid-way between two of the chimneys 27. When the turntable 16 is turned to the position corresponding to Fig. 10, the flames of all of the cans but one will be extinguished, and the flame of the single can will be sufficient to keep the utensil above the stove warm. When it is desired to extinguish all of the flames a cap or cover may be placed over the can beneath the chimney 27^a by slightly raising the turntable.

In accordance with the provisions of the patent statutes the principle of the invention, together with what is now considered to be the best embodiment thereof, have been described, but it is to be understood that the apparatus described is merely illustrative, and that the invention may be carried out in other ways.

Having now described the invention what is claimed and desired to be secured by Letters Patent is:—

1. A device of the character described, comprising means for supporting a receptacle containing fuel, there being a flame opening in the receptacle, means carried by the support for closing the flame opening,

there being openings in the closing means for admitting air to the receptacle through the flame opening and for permitting egress of flame from the receptacle.

2. A device of the character described, comprising a frame adapted to support a receptacle containing a fuel to be ignited, there being a flame opening in the receptacle, said opening being of less diameter than the receptacle, a member above the receptacle and separated therefrom, there being an opening in the member to admit air through the flame opening to the receptacle to support combustion of the fuel therein, there being an opening in the member to permit of the escape of flames from the receptacle, the combined areas of said openings in the member being approximately equal to the area of the flame opening.

3. A device of the character described, comprising a frame adapted to support a receptacle containing a fuel to be ignited, there being a flame opening in the receptacle, a member above the receptacle, there being an opening in the member to admit air to the receptacle to support combustion of the fuel therein, there being an opening in the member to permit of the escape of flames from the receptacle, and means for adjusting the size of the last mentioned opening.

4. A device of the character described, comprising a frame adapted to support a receptacle containing a fuel to be ignited, there being a flame opening in the receptacle, a member adapted to engage the receptacle, there being an opening in the member to admit air to the receptacle to support combustion of the fuel therein, there being an opening in the member to permit of the escape of flames from the receptacle, a rim around the last mentioned opening, and means for moving the member relatively to the receptacle to diminish the size of the said last mentioned opening.

5. A device of the character described, comprising a frame adapted to support a receptacle containing a fuel to be ignited, there being a flame opening in the receptacle, a rotary member adapted to engage the receptacle, there being an opening in the member to admit air to the receptacle to support combustion of the fuel therein, there being an opening in the member to permit of the escape of flames from the receptacle, a rim around the last mentioned opening, and means for rotating the member relatively to the receptacle to diminish the size of the said last mentioned opening.

6. A device of the character described, comprising a frame adapted to support a receptacle containing a fuel to be ignited, there being a flame opening in the receptacle, a rotary member adapted to engage the receptacle, there being an opening in the member to admit air to the receptacle to support

combustion of the fuel therein, there being an opening in the member to permit of the escape of flames from the receptacle, a rim around the last mentioned opening, means for rotating the member relatively to the receptacle to diminish the size of the said last mentioned opening, and means for rotating the member to close the flame opening of the receptacle and extinguish the flame.

7. A device of the character described, comprising a base, a frame supported by the base, a receptacle adapted to contain fuel carried by the base, there being a flame opening in the top of the receptacle, a member supported by the base above the receptacle and resting thereon, there being a chimney flue in the member communicating with the flame opening, there being an air opening in the member, said opening lying to one side of and in proximity to the chimney, said opening being in communication with the flame opening, means for moving the member from engagement with the receptacle, and means for shifting the member to change the positions of the chimney and opening relatively to the axial line of the opening in the receptacle.

8. A device of the character described, comprising a base, a frame supported by the base, a receptacle adapted to contain fuel carried by the base, there being a flame opening in the top of the receptacle, a member supported by the base above the receptacle and resting thereon, there being a chimney flue in the member communicating with the flame opening, there being an air opening in the member, said opening lying to one side of and in proximity to the chimney, said opening being in communication with the flame opening, means carried by the member for moving the member from engagement with the receptacle, and means carried by the member for shifting the member to change the positions of the chimney and opening relatively to the axial line of the opening in the receptacle.

9. A device of the character described, comprising a base, a frame supported by the base, a plurality of receptacles adapted to contain fuel carried by the base, there being a flame opening in the top of each receptacle, a member supported by the base above the receptacles and resting thereon, there being a chimney flue in the member communicating with each flame opening, there being an air opening in the member, said opening lying to one side of and in proximity to each chimney, said opening being in communication with the flame opening, means carried by the member for moving the member from engagement with the receptacle, and means carried by the member for shifting the member to change the positions of the chimneys and openings rela-

tively to the axial lines of the openings in the receptacles.

10. A device of the character described, comprising a base, a frame carried by the base, there being a plurality of equally spaced sockets in the frame, a fuel receptacle in each socket, there being a circular flame opening in the top of each receptacle, a turntable carried by and rotatable relatively to the base and to the frame, said turntable engaging the tops of the receptacles to close the flame openings, there being a plurality of flue openings in the turntable, said turntable having a plurality of air openings therethrough, there being a flue and air opening for each receptacle, the combined area of an air and flue opening being approximately equal to the area of a flame opening, means for releasing the turntable from the receptacles, and means for rotating the turntable relatively to the frame for adjusting the size of the flame openings.

11. A device of the character described, comprising a base, a frame carried by the base, there being a plurality of equally spaced sockets in the frame, a fuel receptacle in each socket, there being a circular flame opening in the top of each receptacle, a turntable carried by and rotatable relatively to the base and to the frame, said turntable engaging the tops of the receptacles to close the flame openings, there being a plurality of flue openings in the turntable, said turntable having a plurality of air openings therethrough, there being a flue and air opening for each receptacle, the combined area of an air and flue opening being approximately equal to the area of a flame opening, means for releasing the turntable from the receptacles, means for rotating the turntable relatively to the frame for adjusting the size of the flame openings, and means for locking the turntable in position relatively to the receptacles.

12. A device of the character described, comprising a base, a frame carried by the base, there being a plurality of equally spaced sockets in the frame, a fuel receptacle in each socket, there being a circular flame opening in the top of each receptacle, a turntable carried by and rotatable relatively to the base and to the frame, said turntable engaging the tops of the receptacles to close the flame openings, there being a plurality of flue openings in the turntable, said turntable having a plurality of air openings therethrough, there being a flue and air opening for each receptacle, the combined area of an air and flue opening being approximately equal to the area of a flame opening, means for releasing the turntable from the receptacle, means for rotating the turntable relatively to the flame for adjusting the size of the flame openings, a projection on the base, there being openings in the

turntable for engagement of the projection to lock the turntable in position relatively to the receptacle.

13. A device of the character described, comprising a base, a frame carried by the base, there being a plurality of equally spaced sockets in the frame, a fuel receptacle in each socket, there being a circular flame opening in the top of each receptacle, a turntable carried by and rotatable relatively to the base and to the frame, said turntable engaging the tops of the receptacles to close the flame openings, there being a plurality of flue openings in the turntable, said turntable having a plurality of air openings therethrough, there being a flue and air opening for each receptacle, the combined area of an air and flue opening being approximately equal to the area of a flame opening, a cam carried by the turntable and co-operating with the base, a handle for rotating the cam, for releasing the turntable from the receptacles, and means for rotating the turntable relatively to the frame for adjusting the size of the flame openings.

14. A device of the character described, comprising a base, a frame carried by and rotatable relatively to the base, means for locking the frame against rotation, there being a plurality of equally spaced sockets in the frame, a fuel receptacle in each socket, there being a circular flame opening in the top of each receptacle, a turntable carried by and rotatable relatively to the base and to the frame, said turntable engaging the tops of the receptacles to close the flame openings, there being a plurality of flue openings in the turntable, said turntable having a plurality of air openings therethrough, there being a flue and air opening for each receptacle, the combined area of an air and flue opening being approximately equal to the area of a flame opening, means for releasing the turntable from the receptacles, and means for rotating the turntable relatively to the frame for adjusting the size of the flame openings.

15. A device of the character described, comprising a fuel receptacle having a circular flame opening in its top, a member adapted to engage the top of the receptacle and close the opening, there being a chimney in the member adapted to permit egress of flame from the flame opening, there being an air opening in the member in proximity to and to one side of the chimney.

16. A device of the character described, comprising a fuel receptacle having a cir-

cular flame opening in its top, a member adapted to engage the top of the receptacle and close the opening, there being a chimney in the member adapted to permit egress of flame from the flame opening, there being an air opening in the member in proximity to and to one side of the chimney, the combined areas of the chimney and air openings being approximately the same as the area of the flame opening.

17. A device of the character described, comprising a fuel receptacle having a circular flame opening in its top, a member adapted to engage the top of the receptacle and close the opening, there being a circular chimney in the member adapted to permit egress of flame from the flame opening, there being a crescent shaped air opening in the member in proximity to and encircling one side of the chimney, the combined areas of the chimney and air openings being approximately the same as the area of the flame opening, said air and chimney openings being so proportioned that the combined areas may be in communication with the flame opening at the same time. 85

18. A device of the character described, comprising a fuel receptacle, there being a flame opening in the top of the receptacle, a closure for the opening, a chimney carried by the closure for directing the flame from the opening in the closure upward, there being an opening for admitting air to the receptacle through the flame opening, said air opening being in proximity to and to one side of the chimney, the combined areas of the chimney and air opening being approximately equal the area of the flame opening. 95

19. A device of the character described, comprising a fuel receptacle, there being a flame opening in the top of the receptacle, a closure for the opening, a chimney carried by the closure for directing the flame from the opening in the closure upward, there being an opening for admitting air to the receptacle through the flame opening, said air opening being in proximity to and partly surrounding the chimney, the combined areas of the chimney and air opening being approximately equal the area of the flame opening. 105

This specification signed and witnessed Sept. 8th, 1920.
